UNITED STATES PATENT OFFICE.

JAMES CHARLES POTTER, OF PAWTUCKET, RHODE ISLAND.

SPINNING AND TWISTING MACHINE.

Application filed December 24, 1921. Serial No. 524,681.

To all whom it may concern:

Be it known that I, JAMES C. POTTER, residing at Pawtucket, county of Providence, and State of Rhode Island, a citizen of the 5 United States, have invented certain new and useful Improvements in Spinning and Twisting Machines, of which the following is a specification.

The spindles of spinning machines, by the 10 usual practice, are driven by bands in the form of round belts which run from the tin roller to the spindles, there being such a band for each spindle, and by tapes which are flat belts that likewise run from the tin 15 rollers to the spindles, a tape, however, driving 4 spindles and a tension roller being employed for each tape to take up slack therein. The first mentioned or band driving is objectionable because it is subject to 20 variations in tension so that, for example, in damp weather the band stretches and becomes so loose that it slows down the speed 25 of the spindle and is apt to jump the whirl which is objectionable first, because it stops the running of the spindle and time must be taken to replace it, and it climbs or works up the bobbin to the ruin of the yarn wound thereon. When thoroughly dry the band may 30 become so tight as to break. Again, when it is desired to reverse the twist of the yarn say from right to left, every band must be 35 changed so as to reverse the direction of revolution of the spindles. The tape drive from the tin roller is faulty because as a 40 result of the quarter turn of the tape on the run from the horizontal tin cylinder to the vertical spindle on one side of the tin roller, and on the run from the tension roller to 45 the spindle on the other side of the tin roller and the necessity of placing the tension roller to one side of the direct line of draft from the tin roller to spindle, the tape does not bear flat and smooth against the 50 periphery of the tin roller but is slightly askew so that one edge of the tape may have no contact with the tin roller and the work falls upon the other edge and the tape shifts laterally back and forth upon the tin roller, the 55 result being that the drive of the spindles is not steady and the tape rapidly wears out and adds to the dirt produced to the possible injury of the yarn. Should change of twist of yarn, as from right to left, be necessary, it would not be practicable to accomplish 60 that by rearrangement of the tape corresponding with the crossing or uncrossing 65 of the band in the band type of drive. An important object of my invention is to provide a spindle drive which will overcome the 70 defects of the band and tape drives above mentioned. Another important object of my invention is to enable the use of the tape drive as the tape is preferable to the band even when, as in the ordinary practice, 75 above described, the tape is open to the objections I have noted. Still another important object of my invention is the provision of an improved spindle drive in ring-spinning or twisting machines of the type in which the ring-rails are stationary and the 80 spindles are traversed by the builder motion, such a type being the subject of my patent of December 27, 1921. My invention consists in any machine having the characteristics of construction defined by or 85 included within the scope of the appended claims.

In the accompanying drawings which form a part of this specification, I illustrate my invention as embodied in a machine 90 of the type of my before mentioned patent, that is to say, a ring-spinning machine in which the spinning rail is stationary and the spindles traverse through the rings. In such drawings:

Fig. 1 is a top plan view of a portion of a spinning machine embodying my invention;

Fig. 2 is a vertical section on the line 2—2 of Fig. 1;

Fig. 3 is a vertical section on the line 3—3 of Fig. 1.

Proceeding now with a description in detail of what is shown in the drawings, 10 designates the stationary ring-rail, there being, as usual, one at both front and back of the machine, 11, the rings thereon, and 12, the travelers to which the yarn runs from the front feed rollers. The spindles, 13, are supported by a vertically movable carriage that comprises parallel rails, 14, at front and back of the machine which are connected at the ends by cross bars and at intermediate points by samsons, as usual, and by a builder motion, not necessary to 100 show in the drawings, the vertical movement of the carriage to effect the traverse of the spindles through the rings in building the cop is accomplished.

Midway between the spindles from front 110 to back of the machine I mount a series of vertical drums or wide faced pulleys, 15,

there being one, preferably, for two opposite boxes of spindles and from each drum an endless tape, 16, is run to the boxes or groups of spindles associated therewith, 5 each spindle having a whirl, 17, in the form of a flanged crowned pulley and the tape after passing over the whirls of two adjacent spindles passes over an idler pulley, 18, situated in the space between adjacent 10 groups of two spindles, the idlers being so disposed that substantially a quarter turn of the tape about each whirl is accomplished and thus the desired driving grip of the tape on the whirls is assured. The idlers are 15 mounted each on a shaft supported from the spindle rail so that, of course, the idlers partake of the vertical movement of the spindles with their supporting carriage. In the run of the tape from the drum to the 20 first spindle of a box I place a tension pulley, 19, which is slidably supported by a cross-bar, 20, that extends from one carriage rail to the other so that the tension roller while movable horizontally to take up slack 25 in the tape and maintain the desired tension of the tape participates in the vertical movement of the spindles with the carriage and in consequence of such vertical movement of the spindles with their whirls, the idlers 30 and the tension roller, the tape moves vertically sliding up and down over the periphery of the wide-faced pulley and thus at all times in the vertical movement of the spindles the driving connection with the drum is 35 maintained although the drum itself is stationarily supported. The tension roller is mounted on a vertical shaft, 21, that has bearings in a bracket, 22, that has a slidable connection with the cross bar, 20, and said 40 bracket has an eye or ring, 23, which is engaged by a hook, 24, on one end of a rope or chain, 25, which passes horizontally to and over a guide roller, 26, on said cross bar, the rope or chain thence extending 45 downward under the pull of a weight, 27, and thereby the desired tension on the tape is maintained. On the opposite side of its shaft, the tension roller bracket has a similar eye or ring, 28, and on the same side therewith there is another rope guided pulley, 29, so that merely by lifting the tape from engagement with the tension roller as 50 shown in full lines in Fig. 1 and allowing the tape to run directly from the drum to the end spindle of the box and passing the tape where it runs from the spindle to the opposite side of the drum over the tension roller and attaching the weighted rope to the ring or eye, 28, and then reversing the direction 55 of revolution of the tape driven drum, the change of twist may be made from right to left or vice versa. The dotted lines in Fig. 1 show the transposition of tape and weight necessary to reverse the twist. Evidently 60 the operation of reversing the twist is a

very simple one that requires but little time and labor.

Each drum or wide faced pulley, 15, is fixed to the upper end of a vertical shaft, 30, mounted in bearings supported by a horizontal rail, 31, and below such rail has a spiral gear, 32, on a long horizontal driving shaft, 33, is a spiral gear, 34, for each drum shaft, 30, which meshes with the spiral gear, 32, on such shaft, and thus all of the 70 drums are driven by the shaft, 33. At one end the drive shaft, 33, has a pulley, 35, which receives motion from a suitable source and which pulley is rotated in one direction or the other according to whether the twist 75 of the yarn is to be right or left. I do not consider it necessary to show means for driving said pulley. The spiral gears and a step bearing for the bottom of each drum shaft, 30, are enclosed by a box or trough, 80 36, secured to the underside of the rail, 31, which is filled with oil and thus lubrication is readily taken care of and noise eliminated, as the gears run in oil.

The ring-rail, 10, in rear of the spindles 85 has an upturned flange, 37, which extends sufficiently high in rear of the spindles as to form a shield or barrier that prevents lint being blown out on the bobbins and yarn wound thereon and from the front edge of the ring-rail I suspend a board, 38, whose vertical extent is such that it prevents lint blowing through to the front of the machine between the spindles and checks drafts 90 of air that would tend to blow lint upon the bobbins or yarn below the ring-rail. The board, 38, is preferably pivoted by hinges, 39, at its upper edge to the ring-rail so that it may be swung outward away from the spindles or bobbins to give access thereto. 100 By the arrangements described which arrest or divert air blowing from within the machine, not only is a clean condition maintained but the deposit of lint upon the yarn being wound on the bobbins to the injury 105 thereof is avoided.

As I have already indicated, my invention may be embodied in other types of machines than the stationary ring-rail type. It is also to be understood that I do not restrict myself to the particular embodiment of the stationary ring-rail type shown in the drawings when my invention is embodied in the stationary ring-rail type. It is also to be understood that my invention extends to 110 improvements in twisting as well as spinning machines. The scope of my protection therefore is to be ascertained from the following claims.

What I claim is:

1. A spinning or twisting machine having two lines of spindles, a drive pulley mounted substantially midway between the two lines of spindles on an axis parallel with the spindle axes, an endless belt passing in op- 120 125 130

- posite directions from said pulley to the spindles of each line in succession, a tension device over which said belt passes, idlers adjacent the spindles of each line over which such belt passes, and a movable carriage supporting said spindles, tension device and idlers, for traversing the spindles, said belt partaking of the movement of said carriage.
2. A spinning or twisting machine having a plurality of spindle drives comprising endless belts for groups of spindles, a drive pulley for the belt of each group, means for revolving said drive pulleys, the spindles and drive pulleys having their axes of revolution parallel, a stationary support for said pulleys, and a movable support for said spindles and said belts whereby the latter traverse the pulleys.
3. A spinning or twisting machine having a plurality of spindle drives comprising endless belts for groups of spindles, a drive pulley for the belt of each group, and means for revolving said drive pulleys comprising a common drive shaft and a gear connection between same and each pulley.
4. A spinning or twisting machine having a plurality of spindle drives comprising endless tapes for groups of spindles, a drive pulley for the tape of each group, and means for revolving said drive pulleys the pulleys and spindles having their axes of revolution parallel, whereby twist of the tapes is avoided.
5. A spinning or twisting machine having a plurality of spindle drives comprising endless tapes for groups of spindles, a drive pulley for the tape of each group, means for revolving said drive pulleys, idlers adjacent the spindles of each line over which such belt passes, and a movable carriage supporting said spindles, tension device and idlers, for traversing the spindles, said belt partaking of the movement of said carriage.
6. A spinning or twisting machine having two lines of spindles divided into groups for drive purposes, a carriage upon which such spindles are mounted, a stationary ring-rail, drive pulleys corresponding in number to the groups of spindles to be driven, an endless belt passing between said drive pulley and the end spindle whirl of groups on opposite sides of said pulleys and thence passing in succession to the remaining spindle whirls of such group and extending between the last spindles of both lines of a group, a tension pulley over which such belt passes, and a cross bar of the carriage upon which such tension pulley is movably mounted, the axes of drive pulley, spindles, and tension pulley being parallel.
7. A spinning or twisting machine having a drive pulley whose axis of rotation is parallel with the spindle axes, an endless belt passing from the pulley to spindle whirls in succession, and a tension device over which such belt passes, said belt being shiftable between the opposite sides of the tension device to change the direction of twist of the yarn.

In testimony whereof I hereunto affix my signature.

JAMES CHARLES POTTER,
